(57) **CLAIM**

The ornamental design for a razor, as shown and described.

DESCRIPTION

1. Razor
- 1.1 : Perspective
- 1.2 : Front
- 1.3 : Back
- 1.4 : Top
- 1.5 : Bottom
- 1.6 : Left
- 1.7 : Right

The stipple shading in the drawings represents contours and does not illustrate surface ornamentation or decoration; the broken lines of the design are directed to the environment and are for illustrative purposes only and form no part of the claimed design.
